UNITED STATES PATENT OFFICE.

GUSTAF W. NYQUIST, OF MINNEAPOLIS, MINNESOTA.

DEVICE FOR PUMPING AIR OR OTHER FLUID.

1,088,870.

Specification of Letters Patent.

Patented Nov. 18, 1913.

Application filed September 18, 1912. Serial No. 720,984.

To all whom it may concern:

Be it known that I, GUSTAF W. NYQUIST, a citizen of the United States, residing at Minneapolis, in the county of Hennepin and State of Minnesota, have invented certain new and useful Improvements in Devices for Pumping Air or other Fluid, of which the following is a specification.

My invention relates to a centrifugal device for pumping air or other fluid.

It is the object of my invention to provide rotating means for drawing in air or other fluid and forcing the same at high pressure therefrom, said means being provided with valve mechanism which shall be effective to absolutely seal the pump from back pressure of the pumped fluid into the air chamber.

It is also an object of my invention to provide a device of the above type which shall be simple in construction and operation and peculiarly available for lubrication.

The full objects and advantages of my invention will appear in connection with the detailed description thereof and are particularly pointed out in the claims.

In the drawings, illustrating the application of my invention in one form, Figure 1 is a side elevation with some parts broken away. Fig. 2 is a central longitudinal section. Fig. 3 is a section on line 3—3 of Fig. 2. Fig. 4 is a view similar to Fig. 3 showing the parts in a different position. Fig. 5 is a sectional view on line 5—5 of Fig. 1. Fig. 6 is a sectional view on line 6—6 of Fig. 3. Fig. 7 is an end elevation viewed from the right hand side of Fig. 1.

A casing is provided comprising a central tubular portion 10 having a semitubular offset 11, said tubular portions being bolted to end members 12 and 13, respectively, the member 13 having opposite the center of tubular portion 10 an enlargement 14 providing a chamber 15 and an upstanding enlarged portion 16 providing a passageway 17 leading from chamber 15, which passageway 17 may be connected with a pipe 18, if desired. The tubular portions 10 and 11 are bifurcated centrally and formed with flanges, as indicated at 20 and 21 in Figs. 1 and 2, a centrally bifurcated ring 22 dividing the chamber within portion 11 into two sections and having a portion 23 extended within the chamber formed within the tubular portion 10 for a purpose later to be given. Journaled within the end members 12 and 13 and extending through diaphragm ring

22 centrally with respect to the chamber within portion 11 is a shaft 19 having thereon a rotary valve member 24, which is a closed cylinder provided with a semicircular cut-out portion 25 at one side, a chamber 26 at the other side being cored out from the body of the cylinder to balance the weight of the same for driving purposes. The valve member 24 is placed at one side only of diaphragm ring 22, as clearly shown in Fig. 2. On the other side of diaphragm 22 is secured to shaft 19 a member 27 similar to member 24 excepting that it is provided with an open portion 28 on the opposite side of the shaft 19 from open portion 25. A cylinder member 29 has an open tubular extension 30 journaled in a bearing 31 formed in end wall 12. Said member 29 has secured to the opposite end thereof a shaft 32 to which a pulley 75 driven from a source of power may be attached and the tubular portion 30 is provided with a gear 33 meshing with the pinion 34 on shaft 19 so that the members 24 and 27 on shaft 19 and member 29 will be 80 simultaneously driven in opposite directions. In practice, members 24 and 27 will be of smaller diameter than member 29, and the relation of gears 33 and 34 is such that one rotation of gear 33 will produce one rotation 85 of gear 34. The member 32 is provided with a pair of curved partitions 35 and 36 forming two chambers 37 and 38, respectively, chamber 37 being terminated at a point about midway of member 29 by an end wall 39, while chamber 38 extends clear through to the end of member 29 being terminated by a partition or end wall 40. Both chambers 37 and 38 open indirectly into the chamber 15, as clearly shown in Fig. 2. The space 95 without the partition walls 35 and 36 forms chambers 37 and 38 but within cylinder member 29 comprises chambers 41 and 42 each opening into a common portion 43 which in turn has communication with the opening 44 within bearing extension 30 through which communication with the outside atmosphere is had by chambers 41 and 42.

The member 29, as above stated, is cylindrical and seats within the circular opening in the diaphragm ring 22 being spaced from the wall 10 a distance equal to the inner projection 23 of diaphragm ring 22. Adjacent one junction of partition wall 35 with the wall of member 29 is a port 45 extending through wall 29 and into chamber 37. A

similar port 46 extends through wall of member 29 into chamber 41, and between the ports 45 and 46 extends from member 29 a wing 47 of a height sufficient to just engage the interior of the chamber formed by tubular member 10. At the outside of port 45 is a short partition wall 48 extending obliquely toward wing 47, a similar partition wall 49 extending from outside of port 46 toward wing 47, each of walls 48 and 49 being inwardly curved and terminating short of wing 47 so as to leave a passageway between said wing and the edges of the short walls 48 and 49. As shown on Sheet 1 and 15 also as indicated in dotted lines at 50 in Fig. 5, at the ends of the wing member 47 and short partitions 48 and 49 are terminating walls 51 and 52. It will be seen, therefore, that as wing member 47 moves about 20 and within the annular space 53 between tubular member 10 and member 29, it separates said space into two portions one of which communicates through port 46, spaces 41 and 43 and opening 44, with the atmosphere for intake, and the other of which communicates through port 45, passageway 37, chamber 15 and passageway 17, with the outflow pipe 18. As shown in Fig. 6, the ends of passageways or chambers 41 and 42 25 adjacent chamber 15 are closed by end walls 54 and 55 so that there can be communication between chambers 37 and 41 only indirectly through ports 45 and 46 and annular space 53. A wing member 56, having end walls 57 and 58 and associated ports and short curved partitions similar to ports 45 and 46 and partitions 48 and 49, is provided in relation to chamber 38 which is in all respects similar to the wing member 47 and 30 associated parts for chamber 37 except that wing member 56 and its related parts are positioned on the opposite side of member 29 and so as to operate at the other side of diaphragm ring 22. Wing member 47 operates with the cut-out portion 25 of 35 rotary valve member 24 while wing member 56 cooperates with the similar portion 28 of valve member 27.

The operation of my pump will be apparent from the description thereof. As member 29 is rotated wing members 47 and 56 travel within the annular spaces 53 at each side of diaphragm 22. The valve members 24 and 27 seal up the annular passageways 53 in front of and behind the wing members 47 and 56. Air or fluid in front of such wing members therefore is forced over the lips 48 through ports 45 into chambers 37 and 38 and from said chambers into chamber 15. 40 and through passageway 17 out of pipe 18. At the same time air or fluid will flow in through intake opening 44, chamber 43, passages 41 and 42 through ports 46 into the annular passageways 53 behind wings 47 and 56. As above stated, the members 24

and 29 are rotated at the same speed so that wing members 47 and 48 will in turn be brought within the openings 25 and 28, respectively, to vary the relation of the charge of air in the annular passageways 53 at the end of each revolution of wing members 47. The short curved lips or partitions 48 and 49 enter the openings 25 and 28 in such manner as effectually to seal communication between the high pressure area within passages 70 37 and 38 and the air pressure area with passages 41 and 42 while this change is taking place, one or the other of lips 48 and 49 always being in engagement with an edge of the walls forming the openings 25 or 28. 75 The member 24 runs in close contact with the inner wall of tubular portion 11 and also in contact with the wall of tubular member 29. It is desirable, not only for the purpose of effecting smooth running of the parts 80 and little friction, but also to more effectively seal the parts against leakage, that the members 24 and 27 should be lubricated. This can readily be effected by applying a grease cup 59, as indicated in Fig. 5, by 85 means of which hard oil or other lubricant may be forced in upon the surfaces of members 24 and 27.

The advantages of my improved pump will be apparent. Not only can high pressure be obtained or very rapid flow of fluid, but by reason of the double character of the pump mechanism a high rate of speed may be maintained at a relatively low rate of power. Moreover, the device is peculiarly 90 compact so that a very large pumping efficiency is obtainable from a machine of comparatively small size.

I claim:

1. A centrifugal pump comprising a casing 105 formed with a central cylindrical chamber, a hollow cylinder of less diameter than said chamber rotatably mounted therein, one of the bearings of said cylinder comprising a tubular member in communication with the outer atmosphere, said casing also providing an outlet chamber at the other end of and of substantially the same diameter as the hollow cylinder, a system of partitions dividing the hollow cylinder into two pairs of oppositely positioned passages, one of said pairs of passages having direct communication with the inlet opening only and the other pair of passages having direct communication with the outlet chamber only, a partition 110 about the hollow cylinder dividing the annular space between the walls of the same and the casing into two separated compartments, openings being provided from one of each of said pairs of passages into each of 115 said compartments, said sets of openings being at opposite ends and sides of the hollow cylinder, and locking wings on the cylinder between said respective pairs of openings.

2. A centrifugal pump comprising a cas- 120

ing formed with a central cylindrical chamber, a hollow cylinder of less diameter than said chamber rotatably mounted therein, an inlet opening to the hollow cylinder at one 5 end thereof, said casing also providing an outlet chamber at the other end of and of substantially the same diameter as the hollow cylinder, a system of partitions dividing the hollow cylinder into two pairs of oppositely positioned passages, one of said pairs of passages having direct communication with the inlet opening only and the other pair of passages having direct communication with the outlet chamber only, a partition 10 about the hollow cylinder dividing the annular space between the walls of the same and the casing into two separated compartments, openings being provided from one of each of said pairs of passages into each of 15 said compartments, said sets of openings being at opposite ends and sides of the hollow cylinder, and locking wings on the cylinder between said respective pairs of openings.

3. A centrifugal pump comprising a tubular chamber, a rotary member within said chamber having the walls thereof spaced from the walls of the chamber and being provided with separated intake and outflow pas-

30 sages having ports communicating with the space between the rotating member and the chamber, a centrifugal member of less diameter than the first named rotary member having a portion thereof extending into the aforesaid space and engaging with its periphery the periphery of the first named rotating member, means for rotating the two members at uniform speeds, a wing device 35 on the first named rotating member located between the openings into the passages therein and extending outwardly into engagement with the inner wall of the chamber, said second rotating member having a semi-circular cavity for receiving and permitting the passage of the wing member, and a pair of short curved lips extending from the outside of 40 said openings toward the outer edge of said wing member for entering said cavity before and after the passage of the wing member and engaging the outer edges only of said cavity. 45

In testimony whereof I affix my signature in presence of two witnesses.

GUSTAF W. NYQUIST.
